Des. 225,549
Patented Dec. 19, 1972

225,549

PIN WHEEL TOY OR SIMILAR ARTICLE

Arthur Halpern, 40 E. 9th St.,
New York, N.Y. 10003

Filed Aug. 5, 1971, Ser. No. 169,593

Term of patent 14 years

Int. Cl. D21—01

U.S. Cl. D34—15

FIG. 1 is a front elevational view of the pin wheel toy embodying my new design;

FIG. 2 is a side elevational view thereof; and

FIG. 3 is a partial rear elevational view thereof.

I claim:

The ornamental design for a pin wheel toy or similar article, substantially as shown.
